Application May 14, 1951; Serial No. 226,123

12 Claims. (Cl. 164—73)

This invention relates to a tail cutting device adapted for use in a continuous winding operation to sever and transfer a traveling web from a full roll on a winder or reel to an empty core.

A primary object of this invention resides in a device as set forth in the preceding paragraph which will cut through or pierce the surface of a conveyed sheet, thereby forming a tail or a narrow strip of paper for the purpose of transferring or feeding the entire sheet of paper from one section of the machine, or reel, to the next.

Another object of this invention is to provide a device as set forth hereinabove which, after producing a sufficient length of tail or narrow strip of paper, will move transversely of the conveyed sheet to sever the remaining portion of the same.

An important feature of this invention is the provision of a knife which is controlled both along a vertical axis and a horizontal axis and, accordingly, which will be thrust into the sheet and subsequently carried transversely of the sheet, the entire operating means comprising an electrical device.

Other objects and advantages of this invention will become apparent from the following description when taken in conjunction with the accompanying claims and drawings.

Referring to the drawings, in which is shown a preferred embodiment of the invention, it will be noted that:

Figure 1 is a perspective view of a sheet being conveyed as it would be in the manufacture of paper over the conventional press rolls and into a paper receiving reel.

Figure 2 is a vertical sectional side view showing the entire apparatus comprising the instant invention.

Figure 3 is a rear view illustrating the knife blade and supporting carriage and track with the outer casing removed.

Figure 4 is a top fragmentary view illustrating a portion of the track, the controlling motor, and limit switch, the blade or knife structure being removed.

Figure 5 is a side view of the knife and supporting carriage showing portions of the knife operating structure in section.

Figure 6 is a perspective detail view illustrating the immediate supporting means for the knife blade.

Figure 7 is an electrical schematic diagram of the circuit for controlling the operation of the instant invention.

Figure 8 is a top fragmentary view illustrating the manner in which the knife blade severs the conveyed sheet.

Referring now more specifically to the accompanying drawings, it will be noted that the numeral 10 shows in general a portion of the conveying apparatus which is employed in the manufacture of paper and includes a rotating drum 11. Disposed beneath the surface of the conveyed sheet 12 is the cutting device 14 which comprises the subject matter of the instant invention.

The problem involved in this invention is that of transferring a sheet of paper which is undergoing well-known processing methods from a full reel to an empty one without disturbing the continuous movement of the conveyed sheet. To accomplish such a result without stopping the conveyor necessitates the initial threading of a narrow marginal strip of the sheet, which strip has naturally been severed from the remainder of the sheet. Once the narrow strip has been started on a new reel (in the instant invention by some manual means),

2

the rest of the sheet is severed along an angle, thereby gradually feeding more and more of the sheet onto the new reel until finally, after the entire sheet has been completely severed, a complete transfer has been effected.

With this brief introduction, it should be understood that some structural means has to be provided which will thrust a knife blade into the surface of the conveyed sheet along its marginal edge, allowing the paper to travel forward relative to the knife blade, thereby cutting a narrow strip, and finally the structural means must include a device for carrying the knife blade transversely of the sheet, whereby complete severance may occur.

With reference to Figure 2, it will be noted that there appears two elongated tubular members 16 and 18, one overlying the other, and both being supported by a pair of adjustable standard members 20 and 22. Each of these tubes is hollow throughout and the upper tube 16 is provided with a longitudinal slot 24 which extends substantially throughout its entire length.

Slidably within the upper tube 16 is a cylindrical member 26 providing the bearing element for the movable carriage denoted generally by the numeral 28. The hollow interior of the tube 16 provides a track along which or through which the cylinder 26 may travel. Resting on the cylinder 26 is a base member 30 having suitable upstanding bracket members 32 disposed along the lateral edges thereof. Extending both forwardly and rearwardly of the base member 30 is a bar 34 carrying at the outer end a conventional sprocket wheel 36. A standard 38 is disposed medially of the base member 30 and extends vertically upward. This standard 38 is provided with a large slot or aperture 40 positioned in a central area thereof and for a purpose subsequently to be stated.

The structure of the knife blade 42 and its immediate

supporting parts are seen clearly in Figure 6. Accordingly, it will be noted that the blade 42 is vertically pivotally mounted within a slot 44, normally resting at an angle relative to a vertical axis. As the illustration clearly shows, the slot 44 is provided in a panel member 46 having any suitable configuration. However, the instant invention does provide a means for adjusting the angular position of the plate 42 and such will be seen to be a bolt 48 threadedly received within a bore 50 in the panel member. The panel 46 is pivotally mounted at 60 upon

an angulated bracket 52 and is yieldingly maintained in a substantially longitudinal axis relative to the bracket 52. This yielding or biasing means is accomplished by means of a spring 54 connecting the panel 46 and the bracket 52. Further, a stop means in the form of a bolt

56 adjustable within the upstanding ear 58 is provided. Therefore, it will be seen that if a force is applied to the right hand of the panel 46, as viewed in Figure 6, the knife blade 42 may be swivelled or pivoted around a vertical axis through the joint, as occurs during operation

55 as described hereinafter.

With attention now being directed to Figures 2, 3 and 5, it will be noted that the bracket 52 is provided with a pair of downwardly depending spaced bearing members 62 and 64 and that the same embrace therebetween the upper portion of the standard 38. An articulated linkage connects the bracket 52 with the standard 38 and is formed by a pair of bars 66 and 68 pivoted at their terminal portions both to each other and to the depending bearing members 62, on the one hand, and also to the portion of the standard 38 immediately below the aperture 40.

65 Thus, it will be seen from this arrangement that the knife blade may be moved or reciprocated vertically by applying a force at a point substantially where the bars 66 and 68 are jointly connected.

Referring more particularly to Figures 2 and 4, it will be noted that at one end of the tubular track is a motor 70 having its shaft in a horizontal plane and extending transversely through the tubular members. Substantially along the tangential line of contact between the upper and lower members 16 and 18 is provided a slot of suitable dimensions to permit a rotating sprocket wheel 72 to be received therein. The sprocket wheel 72 is mounted upon the motor shaft and carries thereon a chain or belt 74. At the opposite end of the tubular structure, a similar slot 76 is provided between the upper and

lower tubular members 16 and 18 and a sprocket wheel 78 is fixed upon a shaft 79, the latter being journaled in suitable bearing members exteriorly of the tube, not shown.

The chain 74 is threaded around the sprocket wheels 36 and also over a further sprocket wheel 80 which is supported at the front of the standard 38 by means of suitable brackets. It will be noted that the only break in the chain 74 is where the latter is connected to the bar 68 of the linkage mechanism. For this connection there is provided a pair of eyelets 82 extending at opposite sides of the bar 68. Lastly, as far as the path of the chain is concerned, it will be noted that between the sprocket 80 and the point where the chain 74 is connected to the eyelet 82, the chain must pass through the standard 38 and, accordingly, as previously described, an aperture 40 has been provided. A further feature should be noted in the provision of a lower stop means comprising an upstanding tubular member 84 whereby the downward slideable position of the knife 42 is prevented by an abutting contact between the bar 68 and the tubular stop 84.

As an encasing covering or shield for this entire mechanism, a housing member 86 is provided and the same is secured to the base 30 by a bolted connection to the upstanding bracket 32.

Considering now the electrical circuit for controlling the operation of the motor 70, it will be noted from Figure 7 that the motor 70 is a standard three-phase motor supplied with a magnetic brake 88, not to be considered as a part of this invention. As a means for controlling, and especially for reversing the direction of rotation of the motor 70, there is provided a standard three-phase reversing starter consisting essentially of two sets of magnetic contactors. Each set of contactors consists of four pairs of contacts and, as delineated by the dotted lines, four of these pairs of contacts constitute the forward line starter 90 and the remaining four constitute the reverse line starter 92. In either set of contacts, three pairs of contacts, denoted by the numerals 94 and 96, are the contacts which connect the line voltage to the particular windings of the motor 70 while the remaining contact denoted by the numerals 98 and 100, in either case, is a means for interlocking its respective bank of contacts, as will subsequently be more clearly described.

At the left of the schematic diagram, there will be noted a plurality of push-button type switching elements constructed in a conventional manner to afford momentary contact. Without describing the operation of these push-button switches at the present time, their names will be enumerated for clarity in the subsequent discussion. Accordingly, the upper switch 102 is termed a jog button and will be used initially to raise or thrust the knife upwardly into the sheet of paper; immediately below the jog button is provided a run button 104 used when it is desired to move the carriage 28 across the track 24; next is a reversing switch 106; and lastly there is a stop button 108, the operation of these latter to be brought out more clearly in describing the operation of the device. It should be noted that all of the switches just described are normally in what will be termed the upper position, as seen in Figure 7, and that when the buttons are operated they will be in what will be termed the "down" position.

Illustrated in their normal positions are also four other switches which provide the actual mechanical-electrical relationship between the movement of the carriage 28 and the operation of the control circuit. These switches consist of a normally closed jog limit switch 110, a normally closed stop limit switch forward 112, a normally open automatic reversing limit switch 114, and, finally, a normally closed stop limit switch 116 reverse. Further, by referring to Figure 2, it will be noted that at the left end of the tubular track and mounted on a J-shaped bracket 118 is a spring-urged vertically pivoting arm 120. It should be understood at this point that the arm 120 controls the operation of two of the switches; namely 110 and 116. At the opposite end of the tubular track is a pair of arms 122 and 124, both mounted and operated similarly to the arm 120. However, in this latter case, the arm 122 controls the operation of the switch 112, opening it as the arm 122 is pushed downwardly and the arm 124 controls the operation of the switch 114, closing the same as the arm is pushed downwardly.

The operation of this device is as follows: The elements are positioned as illustrated in Figure 1 and the motivating

power for the conveying and reeling operation is begun, thus enabling the sheet 12 to assume a forward component of motion, as indicated by the arrow. Assuming that the sheet 12 has not been pierced by the knife blade 42 and that the core 126 has received a sufficient amount of paper to warrant transferring the sheet 12 to the core 128, and further assuming that the carriage 28 is positioned at the extreme left end, as viewed in Figure 2, of the tubular track whereby the arm 130 (Figure 5) extending laterally from the base 30 is holding the arm 120 in a downward position, the operation of the device may be commenced. Therefore, the jog button 102 is depressed to the "down" position and thereby a circuit is established from line L¹ through lead 132, through the closed switch 108, and upwardly along lead 134, through the contacts which are bridged by the switch 102 and thereby downwardly along lead 136 through the closed jog limit switch 110 and upwardly through lead 138, through the upper contacts bridged by the switch 106, and subsequently through lead 140 to the forward holding coil 142 through the contacts of a pair of overload relays 144 back to the other side of the line L³, the relays 144 having their operating coils connected in the leads for motor 70.

Energizing of the forward holding coil 142 as described closes the forward contactors 94 and 98 to energize the motor 70, which is shown as arranged to rotate the chain 74 in a clockwise manner, as seen in Figure 2, thereby moving the articulated linkage from an angulated position, as illustrated, to a straight position, as shown in the dotted lines of Figure 5. When the linkage has hit the standard 38, the latter comprising a stop means for the linkage, the knife blade 42 will be at its upper limit of travel and will, because of its position relative to the surface of the sheet 12, have pierced the sheet, as seen in Figure 1. It will be noted that in this position, the blade 42 will have a position which is parallel to the conveyed motion of the sheet 12, thereby permitting effective cutting action of the paper. Since the carriage 28 will move when the linkage mechanism hits the standard 38, some means is necessary to deenergize the motor 70 when such motion begins. Accordingly, at the very instant that the carriage 28 moves, it will be noted that the arm 130 will allow the arm 120 to pivot upwardly, and such action will open the switch 110, thereby deenergizing the motor 70. Under ordinary conditions, this action will never occur, since the operator pressing in on button 102 will generally release the button 102 before the carriage 28 begins to move.

With the knife in the upper position, a narrow strip 148 may be cut and the length of this marginal strip will be determined entirely according to the desire of the user. When such a desired length is reached, the operator manually tears the narrow strip along a transverse line, such as at 150. The portion 152 thus remaining may be threaded by any conventional means around the empty reel 128 and the same will assume a position indicated by the numeral 154.

When the desired amount of threaded strip 154 has been wound on the reel 128, the run button 104 is depressed to the "down" position. It will be noted that the circuit now energized is from line L¹ through lead 132, the switch 108, the lead 134, the run button 104 down contacts through the upper contacts of the button 106 and thence through the forward holding coil 142, and thus back to the line L³. As similarly described, the motor 70 will be energized and now, since the linkage members 66 and 68 are abutting the standard 38, the chain 74 will draw the carriage 28 along the tubular track. It should be noted, however, that since the operator will release the button 104, some interlocked means must be provided to maintain the forward contactors in the closed position. Accordingly, the contactor 98 provides a circuit for the forward holding coil 142, as follows: From line L¹ through lead 132 through the closed switch 108, upwardly through the lead 134, to the upper contacts of the jog button 102, through the lead 156 downwardly through the closed contacts of the stop limit switch forward 112 and thence upwardly through the lead 158 through the closed interlocked contactor 98 and thence through the forward holding coil 142 and back to the line L³.

This movement of the carriage will complete the cutting of the web as indicated by the diagonal portion of the line 152 in Fig. 8, the diagonal direction of the cut being due to the forward movement of the web which takes place during the transverse movement of the car-

riage. The swiveled mounting of the knife at 60 as described is a material aid in establishing properly smooth cutting operation, since while the knife is stationary and cutting the strip 148, it will be aligned parallel with the direction of web travel by the movement of the web, and during its transverse cutting stroke, the knife will naturally adjust itself to the proper resultant angular position for the relative speeds of the carriage and web.

When the arm at the forward end of the carriage, not shown, but similar to the arm 130, strikes the arm 122, thereby depressing the same, the switch contacts 112 will open, thereby deenergizing the circuit through the forward holding coil 142. The momentum of the carriage will carry it beyond the arm 122 to the arm 124 and when the latter is depressed thereby, the reversing limit switch 114 will be closed, thereby energizing the reverse holding coil 160. It should be explained at this point that a manually operable switch 162 is provided in the event that it is not desired to have the carriage automatically returned to the starting position once it has reached the extent of its forward travel. Accordingly, a return and a non-return position is provided for the switch. Therefore, when the switch contacts 114 have closed and the switch 162 is in the return position, the reverse holding coil 160 will be energized through a circuit from L¹ through the lead 132, through the closed contacts of the switch 108, through the return position of switch 162, through lead 164 to the closed contacts of switch 114, and upwardly through the lead 166, through the reverse holding coil 160, and thence back to the line L³. This coil 160 will close the bank of reverse line starter contactors 96 and 100, which, as will be clearly evident from the schematic diagram, reverse two of the phases of the three-phase motor 70, thereby reversing the direction of this motor.

Since the switch 114 will open at the moment the carriage begins its reverse travel, it is believed evident, as in the previous explanation, that an interlock contact 100 is necessary to maintain a circuit for the reverse holding coil 160. This latter circuit may be traced from the line L¹ through the lead 132 down through the closed contacts 108, to the return post of the switch 162, by-passing the switch contact and proceeding through the lead 168 through the closed contacts of the stop limit switch reverse 116 and thence back through the interlock switch contacts 100 to the reverse holding coil 160 back to the line L³. When the carriage reaches the starting position, namely, when the arm 130 abuts the arm 120, thereby depressing the same, the switch contacts 116 will be opened, thereby deenergizing the circuit through the reverse holding coil 160, previously traced.

Several refinements on this circuit should be noted. When it is undesirable to have the carriage return automatically to the starting position, the switch 162 is thrown to the non-return position and it is believed to be clearly evident that no circuit is provided for maintaining the reverse holding coil 160 in an energized state when this switch is placed in such a position. However, since it is necessary to provide some means for bringing the carriage to the starting position, a momentary-type push button switch 106 is provided. It will be noted that if the carriage is at the forward extent of its travel, and if the motor 70 is not energized, then if the switch contacts 106 are placed in the "down" position a circuit will be formed from the line L¹ through the lead 132 to the closed contacts 108, to the now closed contacts of the switch 106 in its "down" position, thence upwardly to the upper closed position of the switch 104 through the lead 170, and thence through the lead 166 to the reverse holding coil 160, and thence back to the line L³. Once again, when the switch 106 is released, the interlock contacts 100 will maintain the circuit through the reverse holding coil 160 until such time as it reaches the initial position where the switch contacts 116 will open, thereby deenergizing the circuit.

Further, it is believed quite evident that if the momentary push button 108 is depressed, then the entire circuit will be precluded from obtaining line voltage, since every circuit must first be energized through the lead 132 from the line L¹. Also, it is believed evident that the motor is protected by the overload relays 144 having their operating coils connected in the leads to the motor 70.

From the foregoing, it is believed that the construction and operation of this automatic paper cutter are readily apparent, and therefore further description is deemed unnecessary.

However, since numerous modifications and equivalents will readily occur to those skilled in the art after a consideration of the foregoing specification and accompanying drawings, it is not intended to limit the invention to the exact embodiment shown and described, but all suitable modifications and equivalents may be resorted to which fall within the scope of the appended claims.

Having described the invention, what is claimed as new is:

- 10 1. A tail cutter of the character described for a traveling web comprising a carriage, means for supporting said carriage adjacent said web for advance and return movement substantially parallel to said web and transversely of the direction of travel of said web, a knife, means mounting said knife on said carriage for movement with said carriage and for movement with respect to said carriage between a retracted position out of the path of said web and a projected position penetrating said web, and operating means for effecting said movement of said knife on said carriage and for effecting said movement of said carriage in timed relation with said movement of said knife to cause said knife to penetrate said web while said carriage is substantially stationary and thereafter to travel with said carriage transversely of said web in cutting relation with said web.
- 15 2. A tail cutter of the character described for a traveling web comprising a carriage, means for supporting said carriage adjacent said web for movement substantially parallel to said web and transversely of the direction of travel of said web, a knife, means mounting said knife on said carriage for movement with said carriage and for movement with respect to said carriage between a retracted position out of the path of said web and a projected position penetrating said web, a drive for effecting said movement of said carriage, and means forming a driving connection between said carriage and said drive responsive to actuation of said drive to shift said knife from said retracted to said projected position thereof for penetration of said web while said carriage is substantially stationary and thereafter to cause said carriage to travel transversely of said web with said knife in cutting relation with said web.
- 20 3. A tail cutter of the character described for a traveling web comprising a carriage, means for supporting said carriage adjacent said web for movement substantially parallel to said web and transversely of the direction of travel of said web, a knife mounted on said carriage for movement between a retracted position out of the path of said web and a projected position penetrating said web, means for effecting said movement of said knife while holding said carriage substantially stationary to cause said knife to penetrate and slit said web lengthwise thereto, and means under the control of the operator and operable following said penetrating movement of said knife to effect said movement of said carriage causing said knife to travel with said carriage transversely of and in cutting relation with said web.
- 25 4. A tail cutter of the character described for a traveling web comprising a carriage, means for supporting said carriage adjacent said web for movement substantially parallel to said web and transversely of the direction of travel of said web, a knife, means mounting said knife on said carriage for movement with said carriage and for movement with respect to said carriage between a retracted position out of the path of said web and a projected position penetrating said web, operating means for effecting said movement of said knife on said carriage and for effecting said movement of said carriage in timed relation with said movement of said knife to cause said knife to penetrate said web while said carriage is substantially stationary and thereafter to travel with said carriage transversely of said web in cutting relation with said web, reversing means for causing return movement of said carriage to the starting position thereof following completion of the cutting of said web, and means responsive to operation of said reversing means for causing movement of said knife to said retracted position in advance of said return movement of said carriage to withdraw said knife from cutting relation with said web.
- 30 5. A tail cutter of the character described for a traveling web comprising a carriage, means for supporting said carriage adjacent said web for movement substantially parallel to said web and transversely of the direction of travel of said web, a knife, a support for said knife on said carriage forming a guide for movement of said knife

between a retracted position out of the path of said web and a projected position penetrating said web, means on said carriage for moving said knife on said support between said positions thereof, said moving means being movable with respect to said carriage in opposite directions to effect said movement of said knife, a reversible drive, and means connecting said drive with said moving means for operation of said moving means upon actuation of said drive to cause said movement of said knife in advance of movement of said carriage.

6. A tail cutter of the character described for a traveling web comprising a carriage, means for supporting said carriage adjacent said web for movement substantially parallel to said web and transversely of the direction of travel of said web, a knife, a support for said knife on said carriage forming a guide for movement of said knife between a retracted position out of the path of said web and a projected position penetrating said web, a reversible drive for said movement of said carriage, a lost motion connection between said drive and said carriage including means mounted for limited movement on said carriage in response to reversal of said drive, and means connecting said lost motion means with said knife to cause shifting of said knife between said positions thereof in response to reversing of said drive and in advance of movement of said carriage.

7. A tail cutter of the character described for a traveling web comprising a carriage, means for supporting said carriage adjacent said web for advance and return movement substantially parallel to said web and transversely of the direction of travel of said web, a knife supported on said carriage for movement between a retracted position out of the path of said web and a projected position penetrating said web, a reversible drive for effecting said movement of said carriage, means connecting said drive with said carriage and said knife and responsive to actuation of said drive in the direction for advancing said carriage to project said knife into said web and thereafter to cause said knife to travel with said carriage transversely of and in cutting relation with said web, and said last named means being responsive to reversal of said drive to the direction for return of said carriage to retract said knife from said web in advance of return movement of said carriage.

8. A tail cutter of the character described for a traveling web comprising a carriage, means for supporting said carriage adjacent said web for advance and return movement substantially parallel to said web and transversely of the direction of travel of said web, a knife supported on said carriage for movement between a retracted position out of the path of said web and a projected position penetrating said web, a reversible drive for effecting said movement of said carriage, means connecting said drive with both said carriage and said knife and responsive to actuation of said drive in the direction for advancing said carriage to project said knife into penetrating relation with said web, means responsive to operation of said last named means for stopping said drive to hold said carriage substantially stationary causing said knife to slit said web, and means under the control of the operator for thereafter reactuating said drive to cause said knife and carriage to advance in cutting relation with said web.

9. A tail cutter of the character described for a traveling web comprising a carriage, means for supporting said carriage adjacent said web for advance and return movement substantially parallel to said web and transversely of the direction of travel of said web, a knife, means including a toggle linkage forming a connection between said knife on said carriage and effective upon straightening thereof to move said knife into a projecting position penetrating said web and upon collapsing thereof to shift said knife to a retracted position on said carriage out of the path of said web, a reversible drive for said carriage, and means connecting said drive with said toggle link-

age adjacent the pivotal joint thereof to cause said straightening movement of said linkage upon actuation of said drive in the direction to advance said carriage and to cause said collapsing movement of said linkage upon actuation of said drive in the direction to return said carriage.

10. A tail cutter of the character described for a traveling web comprising a carriage, means for supporting said carriage adjacent said web for movement substantially parallel to said web and transversely of the direction of travel of said web, a knife mounted on said carriage for movement between a retracted position out of the path of said web and a projected position penetrating said web, means for effecting said movement of said knife while holding said carriage substantially stationary to cause said knife to penetrate and slit said web lengthwise thereof, means under the control of the operator and operable following said penetrating movement of said knife to effect said movement of said carriage causing said knife to travel with said carriage transversely of and in cutting relation with said web, and means forming a swivel mounting for said knife with respect to said carriage causing said knife to align itself with said web following penetration thereby of said web with said carriage stationary and to adjust the angular position thereof during cutting movement with said carriage in accordance with the relative speeds of said web and said carriage.

11. A tail cutter of the character described for a traveling web comprising a carriage, means for supporting said carriage adjacent said web for movement substantially parallel to said web and transversely of the direction of travel of said web, a knife, means supporting said knife on said carriage for movement between a retracted position out of the path of said web and a projected position penetrating said web, operating means for effecting said movement of said knife on said carriage and for effecting said movement of said carriage in timed relation with said movement of said knife to cause said knife to penetrate said web and thereafter to travel with said carriage transversely of and in cutting relation with said web, and means forming a swivel mounting for said knife with respect to said carriage causing said knife to adjust the angular position thereof with respect to the path of said web in accordance with the relative speeds of said web and said carriage.

12. A tail cutter of the character described for a traveling web comprising a carriage, means for supporting said carriage adjacent said web for movement substantially parallel to said web and transversely of the direction of travel of said web, a knife, a support for said knife mounted on said carriage for movement between a retracted position holding said knife out of the path of said web and a projected position causing said knife to penetrate said web, operating means for effecting said movement of said support on said carriage and for effecting said movement of said carriage in timed relation with said movement of said support to cause said knife to penetrate said web and thereafter to travel with said carriage transversely of said web in cutting relation with said web, and means forming a swivel connection between said knife and said support causing said knife to adjust the angular position thereof with respect to the path of said web in accordance with the relative speeds of said web and said carriage.
